UNITED STATES PATENT OFFICE

LOUIS M. LLORENS, OF LOS ANGELES, CALIFORNIA, ASSIGNOR TO AUTOMATIC WORD COUNTER, INC., A CORPORATION OF NEW YORK

TYPEWRITER WORD REGISTER

Application filed April 16, 1925. Serial No. 23,550.

This invention relates to typewriting machines and especially to a word counting register combinable with and operative by such machines to enable the automatic counting of 5 actions of certain elements of the typewriter, such as the letter keys, the figure keys and special character keys, which latter may vary in different keyboards.

In my present invention I employ a mechanism including an actuator of the same general type as that disclosed in my application filed Aug. 23, 1924, now Patent No. 1,604,223, and in which an actuator, of semi-automatic action, is set or prepared for action upon a 15 totalizer by any writing key depressed, excepting punctuation keys not to be counted as words, and which actuator is subsequently released to automatically function when one of a given group of keylevers, or other selected 20 levers, is struck following completion of a word, number or certain symbol writing.

Such release keys and levers, in the present instance, include the space bar, the tabulator keys, and the ordinary punctuation 25 keys.

An object is to provide for a counting of a word by a carriage action, in event of omission, by the typist, to touch some other key which would effect a count, precedent to return of the carriage, and in this connection 30 an object is to provide means cooperative with the "margin release" finger piece of a certain machine, namely the Remington; though this combination may be adapted to 35 other types.

An object is to provide a "cut out" key which is set and locked by a nearly straight down finger push which greatly facilitates its operation by the typist when it is desired 40 to wholly negate the counter from any action by the typewriting machine. In this connection it is also an object to provide for the action of the "cut out" key to render a "clear" key and the "add" key of the counter ineffective 45 so long as the "cut out" key is locked.

In certain cases it may be desirable to provide for stroke of a keylever in lower case without a release or counting action, as when the diagonal bar, /, is in lower case position, 50 and yet to accomplish such release or count

by the same keylever when a "shift key" has raised the typewriter carriage to an upper position for upper case character, as when the bar, /, is below the question mark, ?. Therefore, I provide means operative by and with a "shift lever" action to render desired upper position character keys effective in securing a counting action. 55

An object is to provide for the mounting of the counting mechanism and its associated action, upon a given make typewriter by means which are attachable to the regular organization without specially drilling or otherwise altering. 60

An object is to provide for such an action of the counting means as to prevent a word count at any time desired, and this without disturbing the registered count shown by the counter. In other words, means are provided to unlock the prepared actuator so 70 that the mistake stroke of a keylever will not be counted. 65

Wherewithal, an object is to provide a word register which is of reliable and accurate action, is inexpensive in structure, substantial, of light operative resistance, and can be easily built into or added as an attachment to, a given typewriter machine. 75

Further objects and advantages will be made manifest in the following specification 80 of one embodiment of apparatus of the invention; it being understood that other modifications, variations and adaptations may be resorted to within the spirit of the invention and its scope as is here claimed. 85

Figure 1 is a perspective and elevation, in diagrammatic relation, of the word register as adapted to the Remington typewriter machine.

Figure 2 is a plan and sectional detail of 90 the "margin release" and a release thrust rod associated therewith.

Figure 3 is a plan of a typewriter keyboard, in part, and the associated word register.

Figure 4 is a detail, in plan, of the shift 95 means of the release bar.

Figure 5 is a perspective of a snap hook connecting related parts.

Figure 6 is a right hand, side elevation of 100 register mechanism; normal position, and

Figure 7 is an elevation of the opposite side thereof.

Figure 8 is a plan of the registering mechanism.

Figure 9 is a perspective of the totalizer checking tumbler.

Figure 10 is a vertical, longitudinal section of the register frame, showing the tumbler in checking position and the "clear" lever de-

10 pressed.

Figure 11 is a cross-section on line 11-11 of Figure 10.

Figure 12 is a longitudinal, vertical section of the register showing the "cut out" key 15 depressed and locked, and holding down setting and releasing levers and the actuator.

Figure 13 shows, in elevation, the actuator set for action upon the totalizer.

Figure 14 shows the register mechanism 20 in fully open or released position, immediately following a counting operation of the actuator.

Figure 15 is a front end elevation of the register.

Figure 16 is a rear end elevation of the register.

Figure 17 is a perspective of portions of elements cooperative for unlocking action of the actuator.

30 The embodiment has a base plate 2 on which are side frame plates 3 and 4 which are generally similar and have windows 5 in which play some of the register parts. The mechanism within the frame is preferably enclosed by a box 6 which also covers the shanks of a clearing key C and an adding key A extending in front of the box to be easily accessible at one end of the typewriter with which the register is combined.

40 The inner edge of the plate 2 is off-set and has an upturned flange 2^a to be positioned against the inner face of the usual machine frame F which, in the present type, has a pair of axis screws S'-R' on which are respectively pivoted the usual space bar rock shaft S and ribbon shift rail rock shaft R. On the screws S'-R' are clamp nuts 7 securing the flange 2^a in place so that the base 2 extends out under the frame F.

50 The rock shaft S extends under the forward arms of the usual keyboard levers K and to it are attached the space bar levers L.

55 Loose on the rock-shaft R is a bracket 15 carrying one end of a bar 16 lying parallel to the shaft R and having on its other end a bracket 17, also loose. The bar 16 thus may tilt freely on the shaft R and comprises means for controlling word registering, operative by certain keyboard elements of the 60 typewriting machine.

Mounted on rock-shaft S are loose brackets 18 carrying a bar 19 which is universal to the keyboard writing levers and is operable by all of them, excepting the keys of the 65 punctuation marks ?, --, :--;--. This

universal bar 19 is shown as having a notched upper edge and this is for the purpose of obtaining an uniform degree of depression irrespective of the differential stroke of the different tiers of keylevers K.

The notches 19^a are so deep that the respective superjacent keylevers K will not engage or depress the bar 19. All other writing keys will.

Court, public and general use of typewriting machines by operators desiring to count words written, ordinarily count a number comprising one or more digits and fractions as one word. In this system of counting the bar 16 has teeth 16^a so disposed as to be engaged only by the punctuation keylevers—

70 The bar 16 has one arm 15 attached to a bowed link 11, under shaft R, which is attached loosely to a bell crank 12 secured by a screw 14 on a sleeve or hollow shaft 13 which is loose on an inner shaft 10; these shafts 10-13 passing under the frame F and into the side walls 3-4 of the register frame.

75 One of the bracket arms 18 of bar 19 is attached by a link 18^a to a forwardly extending lever arm 10^a secured on the central shaft 10 which projects beyond the sleeve shaft 13.

80 The actions of the universal bar 19 and the release bar 16 control operation of a suitable totalizing apparatus.

85 This is shown as having a clearing spindle 20 provided with a pinion 21 engaged by a segment of a gear 22 pivoted on a stud 23, Fig. 7, an arm 24 of the segment 22 being attached to a spring 25 normally retracting the segment. A compound lever device is employed to operate the segment and includes the clearing key C which is pivoted at 26 on the register wall 4 and has a leg C' attached to spring 25. When the key C is depressed to position of Fig. 10, it engages a roller 22^a on the segment and swings the segment 22 up and spins the pinion 21 a full revolution. The counting totalizer, which is not specifically here claimed, has a series of digit wheels 30 which are spaced along the spindle 20 and have rigid ratchet wheels 31 and star wheels 31^a. Each wheel 30 has a carry over pawl 33 (Figs. 8 and 10). When the spindle 20 is turned the wheels 30 are all turned to a zero position at a window 36 in the box, by suitable means, not here disclosed, but of the type shown in my previously alluded to patent.

90 Check means are provided to prevent any over-throw of the wheels 30 when they are spun to the clear position, and here includes a tumbler 37 having rigid stop hooks 38. The tumbler is mounted on a cross pivot 61 in the plates 3-4 and a spring 40 normally pulls the hooks back from the orbit of the pawls 33.

95 When the clearing key C is pressed segment 22 swings around and carries a lug 41 up against a cam face 42 of the tumbler and this is tilted in so that when the pawls 33 get

to stop hooks 38, these are in stopping position and stop the wheels 30 at zero position.

The totalizer actuating means

5 Just under the wheels 30 is a cross-pin 45, Fig. 12, and on this is pivoted a series of clicks 50 each having at its upper end a centering wedge 50^a to engage in the successive notches of the respective star wheel 31^a of its wheel 30 so as to quickly press each wheel 10 digit to a true indicating position under the window 36. Each click 50 has a spring 51 attached to a part thereof.

Below the pin 45 is a cross-strap 46 having 15 side arms 48 pivoted on screws 47; one arm having a roller 48^a. These arms carry a cross-bar 49 so disposed that in its upper position it will lie behind angle notches 50^b of clicks 50 and prevent the clicks from releasing the star 20 wheels 31^a.

The first (or unit) ratchet wheel 31, Fig. 14 is engageable and operated by an "actuator" which includes a feed pawl 55 which is pivoted on a pin 56 and pressed toward its wheel 25 31, by a spring 57, all on a "setting lever" 65. The feed pawl 55 has a prong 58 extending under a push-pin 54 which is attached to a "cut out" device, later described. The prong 58 is normally pressed up against the push-30 pin 54 by spring 57 and when the prong is so engaged the pawl 55 is held back away from the unit wheel ratchet 31 but if the supporting pivot 56 moves down, with setting lever 65, then the pawl is pressed by its spring 57 35 in to engage the ratchet wheel.

A latch 60, Fig. 17, is pivoted on a cross pivot 61 just above the bottom of the plate 2 and has a notch to take over the pin 56 and also has a tail 60^a under a release lever 70.

40 The setting lever 65 is secured at its hub on the inner end of the inner shaft 10 Figs. 13, 14, and 16, and when any writing key lever of the typewriting machine is depressed in word, number or special character writing, 45 the setting lever sweeps down and carries with it the actuating pawl 55 and its pin 56 which projects under the nose of the latch 60, which latter is snapped over the pin 56 by action of a spring 66. As the pawl moves 50 down it presses into engagement with the ratchet 31. At this time the setting lever 65 is tensioning an actuating spring 53, Fig. 13. The lever 65 thus is an actuating means.

Thus a depression of the universal bar 19 55 rocks shaft 10 and the lever 65 is tipped down to set the pawl 55, carried by it, for action upon the totalizer and this will be effected when any typewriter element is operated that will tilt the release bar 16 or the hollow shaft 60 13. This shaft has lever 70 which is swung up by a spring 71. Thus when the hollow shaft 13 is rocked to press the lever 70 down this latter will engage the tail 60^a of the latch 60 and tip the latch off the pin 56 and allow 65 spring 53 to actuate the pawl 55 and the en-

gaged ratchet 31 and first wheel 30 (or additional wheels in a carry-over action), giving one tenth revolution at a step.

While the actuator-lever 65 is in lower position it serves to unlock the clicks 50 so that 70 they may yield as the count is made. To that end the cross-bar 49 is tilted down by the near end of the lever 65 which is slotted at 65^a to receive the bar 49, and will hold the bar in upper click locking position to prevent overthrow 75 by rotation.

When a letter key is depressed the hook 60 locks the lever 65 and ratchet 55 prepared for action, but when a special key is struck both the bars 16-19 move down concurrently and 80 the hook 60 is held out by the release lever 70 which prevents the hook from locking the actuator and this immediately moves up and effects a count of the stroke.

In some cases it is desirable to manually 85 add to the totalizer count and I provide means for such purpose. This includes the add key A which is pivoted at 73 (Fig. 6) on plate 4 and has a lateral horn 77 held just above the setting lever 65 and lever 70 by a spring 78 90 attached to key A. Pressing down the adding key depresses concurrently the levers 65-70 and as the lever A is released the actuator gives the unit counter a tenth of a turn.

The "cut-out" device includes a key O 95 slotted at 80 to ride across a fixed pin 81, Figs. 12-14; the upper end of the slot being hooked at 82^a so as to lock the key O under the pin 81, when depressed. The key O is mounted on push-pin 54 which is fixed on a lever 82, 100 and as this goes down it depresses the setting and releasing levers 65-70. A spring 81^a (Fig. 16) attached to push-pin 54 serves to lift the key O and its parts including lever 82 which is pivoted on a screw 83 on plate 4 and has a foot 82^a to swing against roller 48^a and depress the click lock 49 to allow the star wheels to spin. The swinging end of the lever 82 has a cam face 82^b (Figs. 10 and 14) engaged by a roller 82^c on the inner face of 110 the clearing lever C, Fig. 10. Thus the clear lever tilts the foot to unlock the clicks 50. It also, by action of pin 54, releases the set lever 65.

The lever 82 has a lug or roller 82^d, Fig. 7, 115 on its end to move down behind the heel, bearing roller 22^a, of the segment 22 to lock it against action of the clear key-lever C while the cut-out key is down. The add key, too, is out of commission when the cut-out key is 120 locked down.

The counter can be entirely neutralized from typewriter action by merely pressing down the cut-out key until it hooks under the retainer 81. To restore the counter for 125 machine action it is only necessary to tilt the key O out of the locked position. When in cut-out position the bars 16-19 are held down below touch of the keyboard parts. A simple down thrust of the cut-out key will 130

trip off the set lever 65 and therefore negative an error not to be counted, and also when a word is divided at the end of a line.

When the clearing key C is depressed to clear the totalizer it also unlocks the possibly locked lever 65 and its pawl 55. This is done by roller 82^a engaging the lever arm 82 which carries push pin 54 down on levers 65—70 and so trips off the holding latch 60. The clearing key C does not act to unlock the set cut-out key O, and this latter both cuts out and cuts in the counter as a whole.

The typist, counting words written, learns to strike the space bar at the end of a line so as to release the set actuator if the last stroke completed a word at the end of a line. But I provide means operated by the return of the carriage, a part of which is shown at M, to insure register of the finished word should the typist fail to count by the space bar. The carriage has fixed and adjustable left hand margin stops P and P' designed to engage a central "marginal release" member E slidably mounted on a front fixed part X of the typewriting machine.

This member E is engageable and thrust sidewise by a thrust rod 90, axially movable below the part X, and being operative on a wire link 92, as through a bell crank 89, which is attached to a lever arm 93, Fig. 1. This arm is pivoted on pin 94 and has an L-end 93^a attached by a link 95 to crank 12, which as stated is fixed on hollow shaft 13. The effort of spring 71 on lever 70 serves to push the link 92 upward and the thrust link 90 left endwise. Hence the actuating pawl-lever 55—65, having previously been "set" by a writing stroke of a keyboard element, the engagement of the margin release E by a stop P—P' will react on the link 92 and this will cause the lever 12 to be pulled over in a releasing action of shaft 13 and a count effected.

The space bar actuation of the releasing means is accomplished as follows: One of the space bar levers L, Fig. 1, in moving down will engage an arm 96, here connected to lever 93.

Since it may be necessary to operate the release bar 16 by a keyboard keylever K in only one case writing position means are provided to render the predetermined keys effective on one kind of case strokes but ineffective on the other case strokes. For instance in a Remington here concerned the ? is in upper case above the diagonal bar (/), and only the ? mark stroke is utilized as a release action by its key. Therefore, I here mount the bar 16 for lateral shift when the shift key means is actuated to lift the carriage. This means includes the usual shift lever frame D to which is attached a lift post D'. To this post I attach a link 98, Figs. 1 and 5, which is snapped into a slotted arm 99 of a bell crank having an arm 100 with its end disposed against the near side of lever 15, which is

pressed against the arm 100 by a helical spring 101 arranged, conveniently, on rock-shaft R.

When the carriage is shifted to upper case writing position the lever 100 moves over and presses the bar 16 to a position in which one of its lugs 16^a will take a place beneath the ? lever and the release or count effecting bar 16 will tip down with the lever when the ? mark is written. The other lugs on the bar 16 have coaction with the other punctuation keys in either position of the bar endwise, as their length is sufficient for the bar shift.

When a tabulator key TAB is depressed it moves a reach link 102, Figs. 1 and 3, which is provided with a finger 103 movable against a striker 104 which is attached to arm 17 of bar 16. Therefore, the tabulator keys effect a count by the totalizer.

Practically the entire registering organization is shown in its applied position Fig. 1, the side frame of the typewriting machine being omitted as confusing. The chart of characters above the universal bar 19 clearly shows the relation of the bar lugs to the several keyboard keys. Keys effective on the release bar 16 are similarly graphed. Push rod 90 is never pushed far enough to make the release key E lock the key board.

What is claimed is:

1. In a typewriter, a centrally disposed shiftable margin release finger member, a stationary front bar on which said member is mounted, and a word registering mechanism controlled by said member and including a thrust rod pressing said member in one direction and which is repressed by carriage action on said member.

2. A typewriter word register including a totalizer, an actuating pawl therefor, a setting lever on which the pawl is pivoted, a spring means for actuating said pawl and lever in driving action upon the totalizer, keyboard key controlled means for preparing said lever and pawl for action on the totalizer, a setting-lever latch, and typewriter operative means for tripping the latch to release said pawl and lever for actuating effect, said setting lever having a shaft extended from the totalizer and being connected to an universal comb bar.

3. In a typewriter word register, an actuator release device including a release shaft, a shiftable, operating member connected to said shaft, means attached to a tabulator element and operating said member, said operating member comprising a bracket bar pivoted on a support, independently of said shaft, and sliding thereon and having a lug engageable by the said means.

4. A typewriter word register including a totalizer, a machine operated rock shaft, a setting lever on said shaft, a latch to hold the lever set, an actuating spring for the lever, a feed pawl yieldingly mounted on

- the lever, and a cut out key for engaging the pawl and said lever to render them inoperative by the machine action.
5. A typewriter word register including a totalizer, a machine operated rock shaft, a setting lever on said shaft, a latch to hold the lever set, an actuating spring for the lever, a feed pawl yieldingly mounted on the lever, cut out means engageable with the pawl, lockable positioning clicks for the totalizer controlled by said lever, and means for unlocking the clicks. 70
6. A totalizer shaft carrying a loose sleeve, a lever fixed on the shaft, a bell-crank fixed on the sleeve, a rock-shaft and a key actuated comb laterally yieldable and pivoted on the shaft, a sliding and pivotal link connected to the bell crank, and an universal comb connected by a link to the said lever whereby said totalizer shaft and sleeve are operated one relative to the other. 75
7. In a typewriter word register, a totalizer, a stationary shaft, a bar pivotally and slidably mounted on said shaft, and means operative by the shift keys of the typewriter to shift the bar and render the totalizer effective, at will, by a given keyboard writing device when a shift has been made by the shift keys. 80
8. In a typewriter word register, a totalizer, a stationary shaft, a comb bar slidably and pivotally mounted on the shaft, means operative by shift keys of the typewriter to slide the bar on the shaft to an effective position for action on the totalizer, and keyboard means for oscillating the said bar while held in the effective position by said shift key operative means. 85
9. In a typewriter word register, a totalizer, a stationary shaft, a comb bar slidably and pivotally mounted on the shaft, means operative by shift keys of the typewriter to slide the bar on the shaft, keyboard means for oscillating said bar while held by said operative means, and means for automatically restoring the bar to its normal position for oscillation on the shaft. 90
10. In a typewriter word register, a totalizer actuator release means including a pivoted and sliding bar depressible by key levers, means yieldingly pressing the bar endwise, means connected to the case-shift action of the typewriter to shift the bar, and a release lever shaft having a lever operative by said bar at the shifted position; said bar having a link which is slidably and pivotally connected to the last named lever. 100
11. In a typewriter word register, a totalizer actuator having a key actuated setting lever and release means therefor including a pivoted and sliding bar depressible by key levers, means yieldingly pressing the bar endwise, a link connected to said bar and operative on said lever when the bar is tilted, and means connected to the case-shift action 105
